UNITED STATES PATENT OFFICE.

JOHN P. HUBER, OF ST. LOUIS, MISSOURI, ASSIGNOR TO UNITED SHOE MACHINERY CORPORATION, OF PATERSON, NEW JERSEY, A CORPORATION OF NEW JERSEY.

HEEL-CLAMPING DEVICE.

1,409,446.

Specification of Letters Patent. Patented Mar. 14, 1922.

Application filed October 31, 1917. Serial No. 199,554.

To all whom it may concern:

Be it known that I, JOHN P. HUBER, a citizen of the United States, residing in the city of St. Louis and State of Missouri, have 5 invented certain new and useful Improvements in Heel-Clamping Devices, of which the following is a specification.

My invention relates to improvements in heel-clamping devices and has for an object 10 to provide such a device which may be quickly and conveniently operated to clamp a heel to a shoe for holding said heel in position thereon until an adhesive applied to the heel has set sufficiently to hold the 15 heel in position upon the body of said shoe.

A further object of the invention is to provide an element in the form of a removable heel-engaging block adapted to be positioned upon a heel and act as a pressure- 20 distributing element when pressure is brought to bear upon it.

Other objects and advantages will appear in the following specification, and the novel features of the invention will be particularly 25 pointed out in the claims hereto appended.

I attain these objects by the combinations, constructions and arrangements of parts illustrated, as to a particular embodiment of the invention, in the accompanying drawings forming a part of this specification.

Referring to the drawings:

Fig. 1, is a rear elevation of a heel clamp device constructed in accordance with my invention.

Fig. 2, is an end elevation thereof.

Fig. 3, is a detail full size, showing a wood heel clamped to a shoe.

Fig. 4, is a detail showing a portion of a shoe, a last and its support.

40 In carrying out my invention, I employ a suitable bench like table, illustrated in the drawings as consisting of a suitable narrow table top 1 supported by means of suitable legs 2. The device is preferably provided 45 upon its front adjacent the top 1 with a suitable work receiving and supporting shelf 3. The supporting table may be suitably braced as at 4 or in any similar manner to lend rigidity and strength to the 50 structure.

Suitable standards 5 are positioned upon

the top member 1 in suitable spaced relation and are suitably held in fixed relation to the top 1.

A cross-piece 6 is supported by the upper 55 ends of the standards 5 and held in a fixed position thereon by means of the bolts 7 passing through the cross-piece 6 and the securing nuts 8 carried by the upper ends of the bolts 7.

A plurality of last-supporting standards or jacks 9 are fixed in suitable spaced relation to the top member 1. Each standard 9 is provided with the usual last-engaging pin 10, as clearly shown in Figure 1 of the drawings.

An interiorly threaded screw-shaft supporting member 11 is fixed to the under surface of the cross-piece 6 in alignment with each last-supporting standard 9, as 70 clearly shown in Figure 1.

A suitably threaded set-screw or screw-member 12 having its lower end provided with a swivel-head 13 is operatively supported or carried by each interiorly threaded 75 screw supporting member 11. The upper end of each screw member 12 is adapted to be suitably shaped to receive a removable hand-wheel 14 adapted to be manually operated for imparting a rotary up or down 80 movement to the screw-members 12.

One of the features of my present invention is the employment of an improved heel engaging pressure distributing member of a removable unit type, and so designed as to 85 engage both the tread face and a portion of the rear face of a heel being glued to a shoe to distribute perpendicular pressure simultaneously to both the tread and rear face of the heel when pressure is applied 90 to the member.

Each block consists of a body 15 having a flat upper pressure receiving surface 16, and a heel engaging surface 17 adapted to engage the tread face of heels such as 18. 95 Each block 15 is provided with an additional surface 20 which is preferably covered with a suitable pad 21, such as felt or its equivalent. This pad 21 is adapted to engage the back face of the heel 18, as clearly 100 shown in Figure 3, and prevents the rear surface of the heel from being scratched or

defaced. The shape of the face 20 may be varied to fit any form of heel. It is essential though, that the block 15 should be of such shape so as to engage two surfaces 5 of a heel, namely, the tread surface and the rear surface.

When a shoe positioned upon a last 22 is mounted upon any one of the last-supporting standards 9, the next step or operation 10 is to position a heel 18 having glue or other adhesive applied to its heel seat end, upon the body of the shoe, as shown in Figure 3. The next step is then to position a heel-engaging, pressure-distributing block 15 15 upon the heel 18 and turn the screw member 12 in a direction to cause the screw to move downwardly, thereby bringing the swivel-head 13 thereof into engagement with the flat top surface 16. This operation will 20 apply the desired pressure to the block 15, which will, in turn, distribute the pressure exerted thereupon evenly upon the heel 18. The improved means herein described firmly 25 and evenly holds the heel in its proper position upon the shoe body until the glue has thoroughly set. Then the swivel-head 13 is raised by turning the screw in the opposite direction so that the block 15 may be removed from engagement with the heel 30 and the shoe and last removed from the support.

It has been found that by the use of this improved heel-clamping device a shoe may, after the heel has been glued thereto, be 35 passed along and worked upon without first having to remove the last and nail the heel to the shoe from the inside, as is now customary. This is a great advantage, as it does not necessitate the removal of the last 40 until all of the operations, excepting nailing the heel to the shoe, have been performed by the workmen. Hence the shoe better holds its shape, due to the last being therein until it is ready for nailing of the heel there- 45 to and its treeing, dressing and packing, which are the last operations in the course of shoe manufacture when the improved clamping device herein described is used.

With former devices for clamping wood 50 heels to shoes it was found necessary to nail the heels to the shoe's immediately after the glue had set, as they would not stand the strains applied in handling unless the heels were also nailed to the shoe. This necessi- 55 tated the removal of the last from the shoe before the operations were completed. This is not the case with heels which are glued to shoes and clamped into position by means of the device herein described. This is due to 60 the fact that the pressure is properly distributed through the medium of the block 15.

The many advantages of the herein- 65 described invention will readily suggest themselves to those skilled in the art to which it appertains.

I am aware that changes may be made in the construction and arrangements of the several parts of the herein described device, which will still be within the scope of my invention. Hence I reserve the right to 70 make any such changes as may be covered by the appended claims.

What I claim is:

1. A heel clamping device comprising in combination, a standard adapted to support 75 a shoe having a gummed heel seating surface, a vertically disposed pressure-exerting member movable toward and from the heel portion of the shoe, and a heel-pressure-distributing member of such shape and size 80 as to engage both the tread surface and rear surface of a heel having a gummed seat adapted for seating engagement with the gummed heel seating surface of the shoe, said vertically disposed pressure-exerting 85 member adapted to be forced into engagement with the top surface of the heel-pressure-distributing member at such a point along its length as to exert, and equally distribute perpendicular pressure through the 90 heel-pressure-distributing member simultaneously upon both the tread surface and rear surface of the heel when positioned upon the shoe for tightly and uniformly pressing the gummed seat of the heel upon the 95 gummed heel seating surface of the shoe and retaining the heel in a non-slipping position upon the shoe while applying pressure to the heel without initially nailing the heel to the shoe.

2. A heel clamping device comprising in combination, a standard adapted to support a shoe to which a heel is to be secured, a screw-threaded clamping member movable toward and from the standard, and a heel-pressure-distributing member having a heel-engaging surface arranged simultaneously 105 to engage both the tread face and rear face of a shoe heel and to prevent forward and rearward movement of the heel while pressure is being exerted upon the heel-pressure-distributing member, said member being further provided with a flat upper clamp-engaging face disposed in a substantially 110 horizontal plane when the pressure-distributing member is positioned upon the tread surface of the heel to be glued to the shoe and into contact with which face the clamping member may move upon the rotation of its screw.

3. A heel clamping device comprising in combination, a standard adapted to support a shoe to which a heel is to be secured, a clamping member movable toward and from the standard, and a heel-pressure-distributing member having heel-engaging surfaces arranged to meet at the edge of the tread surface and diverging therefrom simultaneously to contact with the tread face and rear face of the heel to prevent displace- 130

ment of the heel upon the shoe when applying pressure to the pressure-distributing member.

4. A heel-pressure-distributing member having a depression furnishing two heel-engaging surfaces, one of said surfaces adapted to engage the tread surface of a heel and to prevent the heel from slipping forward upon the shoe while the pressure distributing member is under pressure to distribute perpendicular pressure throughout the forward portion of the heel, and the other of said surfaces adapted simultaneously to engage the adjacent portion of the rear face of the heel, to prevent the heel from slipping rearwardly upon the shoe and simultaneously to distribute perpendicular pressure throughout the rearward portion of the heel.
5. A heel-pressure-distributing member comprising an integral body having a flat upper clamp-engaging surface, an opposite inclined surface adapted to engage the tread surface of a heel and a curved surface diverging from the inclined surface and adapted simultaneously to engage a portion of the rear face of the heel, both of said heel-engaging surfaces being adapted simultaneously to distribute perpendicular pressure upon the heel when pressure is brought to bear downwardly against the clamp-engaging surface.
6. A wood heel pressure-distributing member of such shape and size as to provide means for engagement with the tread face of the heel to be glued to the heel portion of a shoe after the heel seat of the heel has been gummed with glue and positioned upon the shoe, said means adapted to prevent forward displacement of the heel upon the shoe while perpendicular pressure is being ap-

plied to the pressure-distributing member, and to provide means for simultaneous engagement with the rear surface of the heel to prevent rearward displacement of the heel while perpendicular pressure is being applied to the rear portion of the pressure distributing member, both of said heel-engaging surfaces being so arranged as to equalize the downward pressure applied to the pressure distributing member to prevent displacement of the heel being gummed to the shoe while under pressure.

7. A heel-pressure-distributing member having a main body portion provided with a plane clamp-engaging upper face, said body portion having a plane lower face inclined relatively to the plane of the upper face and adapted to engage the tread surface of the heel of a shoe, and said main body portion being provided with a pendent body portion having a surface meeting the tread-engaging surface and adapted for simultaneous engagement with the rear face of the heel so that pressure on the upper face will be transmitted to the heel in a direction normal to the heel seat.

8. A heel-pressure-distributing member comprising a block having a flat upper clamp-engaging surface, there being a depression in the block furnishing a surface in a plane inclined to the plane of the upper surface and adapted to engage the tread surface of the heel and an adjacent surface adapted to engage the rear face of the heel so that pressure on the upper surface will be transmitted to the heel while slipping thereof is positively prevented.

In testimony whereof, I have hereunto signed my name to the specification.

JOHN P. HUBER.
